ABSTRACT: A side stake structure for a railway flat car including a side stake anchored to a stake pocket and movable to a plurality of positions about the stake pocket for a variety of selected uses. When desired to restrain loads on the flat car against sidewise movement, the side stake is positioned in a vertical direction in the normal manner. When desired to support loads on the deck of a car, the side stake is folded about pivot means to a horizontal position extending transversely of the deck of the car to support loads thereon above the deck. When desired to guide the tires of roadway vehicles, pivot means permit the side stakes to be folded on the deck to a horizontal position longitudinally of the deck of the car to aid in guiding the wheels of roadway vehicles. A modification permits the side stake to form a continuation of the deck surface in a collapsed position thereby providing a flush deck flat car.

FIG. 8.

SIDE STAKE CONSTRUCTION FOR RAILWAY FLAT CARS

BACKGROUND AND DESCRIPTION OF INVENTION

Heretofore, vertically retractable side stakes have been provided with means to permit folding of the side stakes to a retracted horizontal position extending longitudinally of the car alongside the deck or recessed in the deck. Such prior side stakes have not been adapted for folding onto the deck in a transverse direction for supporting loads at a height above the deck or in a longitudinal direction to guide the tires of roadway vehicles and the like.

The present invention provides a side stake mounted in a stake pocket and foldable onto the deck while remaining anchored to the stake pocket. Means mount the side stake for folding onto the upper surface of the deck in a direction transversely of the car and projecting about 6 inches above the deck surface to support loads thereon at a height above the deck. If the railway car is adapted for TOFC service and has collapsible hitches mounted on the deck for securing the kingpins of trailers, the loads will be supported at a height above the collapsed hitches on the deck of the flat car.

When the flat car is adapted for carrying trailers, the side stakes are folded onto the upper surface of the deck in a longitudinal direction along a side of the car with adjacent side stakes being in end-to-end abutting relation to provide a continuous guide rail structure extending the length of the deck.

If desired, the deck may be recessed adjacent the side stakes to receive the side stakes in a retracted position with the side stakes forming a continuation of the deck surface. Also, the side stakes may be pivoted outwardly of the car to provide a bridge for loading and unloading ladings.

The invention accordingly comprises the constructions hereinafter described, the scope of the invention being indicated in the following claims.

In the accompanying drawings, in which several of various possible embodiments of the invention are illustrated,

FIG. 1 is a top plan of a railway flat car embodying the present invention with one-half the length of the railway car being illustrated;

FIG. 2 is a side elevation of the railway flat car illustrated in FIG. 1;

FIG. 3 is an enlarged plan of a portion of the railway flat car shown in FIGS. 1 and 2 and illustrating various positions of the side stake structure comprising the present invention;

FIG. 4 is a perspective of the side stake structure comprising the present invention in which two positions of the side stake structure are illustrated;

FIG. 5 is a plan illustrating the side stake structure of FIGS. 3 and 4 in a position extending outwardly from the flat car to provide a bridging support for loading and unloading ladings;

FIG. 6 is an enlarged perspective of a modified side stake structure which in a collapsed position forms a continuation of the deck surface to provide a flush deck;

FIG. 7 is a plan of an additional modification in which the side stake is of a length generally the same as the width of the railway flat car; and

FIG. 8 is a perspective of a further modification in which a track is arranged in a wall of the side stake structure to receive a tiedown mechanism or the like.

Corresponding reference characters indicate corresponding parts throughout the several views of the drawings.

Referring now to the drawings for a better understanding and more particularly to the embodiment illustrated in FIGS. 1-5, a railway flat car is generally indicated 10 and has an upper deck plate 12 thereon. A center sill structure 14 extends longitudinally of car 10 and a bolster structure 16 is arranged adjacent each end of car 10. A side sill structure generally indicated 18 extends longitudinally along each side of the car and includes an outer angle shaped sill member 20 and an inner side member 22. Angle-shaped outer member 20 includes an outer vertical leg 24 and an upper horizontal leg 26 underlapping deck plate 12 and secured thereto. Inner sill

member 22 includes a vertical web 28 extending downward from the underside of deck plate 12 and an outwardly turned lower horizontal flange 30.

Spaced along the length of deck plate 12 and side sill structure 18 are a plurality of spaced openings or cutouts 32. A sleeve generally indicated 34 is positioned within each cutout 32. Each sleeve 34 comprises a channel-shaped member having an outer plate member 36 and a pair of transverse webs extending between plate member 36 and the adjacent face of vertical web 28. Sleeve 34 forms with vertical web 28 a side stake pocket adapted to receive the side stake structure generally indicated 40 therein and comprising the present invention. Side stake structure 40 includes an anchor portion 42 having an upper loop or link 44 and a lower retainer plate 46 adapted to engage the lower edge of sleeve 34 and limit the upward movement of link 44. Side stake 48 has a lower link 50 in engagement with link 44 to anchor the lower end of stake 48 while permitting stake 48 to move in a generally horizontal plane 360°. The outer end of side stake 48 has an outwardly extending retaining tab 52 adapted to fit within an opening 54 in deck plate 12 when extending longitudinally of car 10 or to fit within opening 56 in deck plate 12 when extending transversely of car 10 as shown in FIG. 3.

Side stakes 48 are of a length approximately one-half the width of deck plate 12 and may be aligned on the upper surface of deck plate 12 in a generally end-to-end relation to provide a guide rail for the wheels of roadway vehicles, such as trailers and tractors. To support ladings, side stake 48 may be moved manually to a position extending transversely of the car as shown in FIG. 3 and ladings, such as banded lumber, may be placed thereon. Side stakes 48 may be positioned in a vertical position, if desired, to restrain the lateral movement of ladings or the like. Referring to FIG. 5, a loading dock D is indicated schematically and side stakes 48 extend outwardly from deck 12 between flat car 10 and loading dock D to provide a bridging support between loading dock D and flat car 10 for the loading and unloading of lading. The connection provided between links 44 and 50 permits a generally pivotal movement of side stake 48 to any of these positions.

Referring to FIG. 6, a modified arrangement is illustrated in which deck plate 12A terminates laterally at vertical web 2 of side sill member 22A. A lower flange 18A of sill member 22A extends outwardly from vertical web 28A. A sleeve 34A of side stake pocket comprises a channel-shaped member 3 secured to the outer face of vertical web 28A and extends outwardly therefrom. Channel-shaped member 34A includes flanges 60 and 62 connected by web 64. Flange 62 has an upper end portion cutout at 66 and an angle-shaped ledge 68 secured thereto below cutout portion 66. A loop-shaped sleeve 70 is secured to the outer surface of flange 60 to receive retaining tab 52A of side stake 48A when stake 48A is in a collapsed position as shown in FIG. 6. Links 44A and 50A are identical to links 44 and 50 in the embodiment of FIGS. 1-5 and permit a generally pivotal movement of side stake 48A in its collapsed position, the lower side of side stake 48A is supported on ledge 68 and the upper side of side stake 48A is for a continuation of deck plate 12A to provide a so-called flush deck flat car.

Referring to FIG. 7, side stakes 48B which extend the width of deck 12B are illustrated. Additional side stake pockets may be provided to receive removable side stakes, if desired. Side stakes 48B may be positioned on deck plate 12B in a direction extending longitudinally of railway car 10A along the sides thereof to provide guide rails for roadway vehicle wheels and the like. Links 44B and 50B connect side stakes 48B for pivotal movement in a generally horizontal plane.

FIG. 8 discloses an embodiment in which side stake 48C is a track or guideway 72 in upper side wall 74 adapted to receive a tiedown structure (not shown) therein. The tiedown structure may be adjusted lengthwise of deck 12C along guideway 72.

In view of the above, it will be seen that the several objects of the invention are achieved and other advantageous results obtained.

I claim:

1. A railway flat car comprising, a relatively flat deck, a plurality of spaced stake pockets extending along each side of said deck, a side stake structure for each stake pocket, each side stake structure including an elongate side stake, anchor means within the associated stake pocket to prevent removal of the side stake from the flat car, and means connecting the side stake to the anchor means to permit a folding of said side stake in horizontal directions longitudinally of the car and transversely of the car, said side stake when folded to a position transversely of the car being supported on the deck and extending in a direction transversely of the deck to support loads thereon above the surface of the deck, said side stake when folded in a direction longitudinally of the car being supported on the upper surface of the deck and projecting upwardly therefrom, a plurality of said side stakes along a side of the car being in generally end-to-end relation when folded in a direction extending longitudinally of the car and forming a continuous rail like member extending the length of the car to provide a guide for the wheels of roadway vehicles moving along the deck of the car.

2. In a railway flat car having a generally flat deck, a side sill structure along each side of the deck forming a continuation of the deck surface thereby not to obstruct the deck, a plurality of openings spaced longitudinally along the length of each side sill structure, a generally vertically extending elongate side stake mounted in each of the openings, anchor means securing the side stakes within the openings and permitting folding of the side stakes from an erect vertical position to collapsed positions on the upper surface of the deck in which the longitudinal axes of the stakes extend longitudinally and transversely of the car, said side stakes when folded to a position extending transversely of the car being adapted to support loadings thereon, said side stakes when folded longitudinally of the deck being in end-to-end relation along each side of the deck and projecting upwardly therefrom to provide a guide for the wheels of roadway vehicles moving along the deck of the flat car.

3. A railway flat car comprising, a relatively flat deck, a plurality of spaced stake pocket structures extending along each

side of said deck, an elongate side stake mounted in each of said stake pocket structures and extending vertically from the stake pocket structure to restrain loads against sidewise movement from the deck of the railway car, and means connecting the side stake to the stake pocket structure to provide folding of the associated side stake from its vertical position to a horizontal position supported on the deck and extending in a direction transversely of the deck to support loads thereon above the surface of the deck, said connecting means between the side stake and the stake pocket structure providing a limited vertical movement of the side stake relative to the stake pocket structure and permitting folding of the associated side stake to a horizontal position extending longitudinally of the deck.

5 10 15 20 25 30 35 40 45 50 55 60 65 70 75

4. A railway flat car as set forth in claim 3 said side stake being of a length to extend across substantially the entire width of the deck when folded on the deck.

5. A railway flat car as set forth in claim 3, said side stake being of a length to extend across around one-half of the width of the deck when the stake is folded to a horizontal position on the deck, the side stakes on one side of the flat car cooperating with the side stakes on the other side of the car to provide a lading support across substantially the entire width of the car.

6. A railway flat car comprising, a relatively flat deck, a stake pocket structure adjacent a side of said deck, an elongated side stake for the stake pocket structure, means connecting the side stake to the stake pocket structure to prevent removal of the side stake from the flat car and to permit folding of said side stake in horizontal directions longitudinally of the car and transversely of the car, said connecting means between the side stake and the stake pocket structure providing a limited vertical movement of the side stake relative to the stake pocket structure, said side stake when folded to a position transversely of the car being supported on the deck and extending in a direction transversely of the deck to support loads thereon above the surface of the deck, and means adjacent the stake pocket structure receiving the side stake in a retracted position not obstructing the deck when the stake is folded longitudinally of the car.

Column 2 should appear as shown below:

... member 22 includes vertical web 28 extending downwardly from the underside of deck plate 12 and an outwardly turned lower horizontal flange 30.

Spaced along the length of deck plate 12 and side stake structure 18 are a plurality of spaced openings or cutouts 32. Sleeve generally indicated 34 is positioned within each cutout 32. Each sleeve 34 comprises a channel-shaped member having an outer plate member 36 and a pair of transverse webs 38 extending between outer plate member 36 and the adjacent face of vertical web 28. Sleeve 34 forms with vertical web 28 a stake pocket adapted to receive the side stake structure generally indicated 40 therein and comprising the present invention. Side stake structure 40 includes an anchor portion 42 having an upper loop or link 44 and a lower retainer plate 46 adapted to engage the lower edge of sleeve 34 and limit the upward movement of link 44. Side stake 40 has a lower link 50 in engagement with link 44 to anchor the lower end of stake 48 while permitting stake 48 to move in a generally horizontal plane three hundred and sixty degrees (360°). The outer end of side stake 48 has an outwardly extending retaining tab 52 adapted to fit within an opening 54 in deck plate 12 when extending longitudinally of car 10 and to fit within opening 56 in deck plate 12 when extending transversely of car 10.

Patent No. 3,550,537 Dated December 29, 1970

Inventor(s) Jan D. Holt et al. PAGE - 2

It is certified that error appears in the above-identified patent and that said Letters Patent are hereby corrected as shown below:

Side stakes 48 are of a length approximately one-half the width of deck plate 12 and may be aligned on the upper surface of deck plate 12 in a generally end-to-end relation to provide a guide rail for the wheels of roadway vehicles, such as trailers and tractors. To support loadings, side stake 48 may be moved manually to a position extending transversely of the car as shown in Figure 3 and loadings, such as banded lumber, may be placed thereon. Side stakes 48 may be positioned in a vertical position, if desired, to restrain the lateral movement of loadings or the like. Referring to Figure 5, a loading dock D is indicated schematically and side stakes 48 extend outwardly from deck 12 between flat car 10 and loading dock D to provide a bridging support between loading dock D and flat car 10 for the loading and unloading of lading. The connection provided between links 44 and 50 permits a generally pivotal movement of side stake 48 to any of these positions.

Referring to Figure 6, a modified arrangement is illustrated in which deck plate 12A terminates laterally at vertical web 28A of side sill member 22A. A lower flange 13A of sill member 22A extends outwardly from vertical web 28A. A sleeve or stake pocket comprises a channel-shaped member 34A secured to the outer face of vertical web 28A and extending outwardly therefrom. Channel-shaped member 34A includes flanges 60 and 62 connected by web 64. Flange 62 has its upper end portion cutout at 66 and an angle-shaped ledge 68 secured thereto below cutout
